UNITED STATES PATENT OFFICE.

EDWARD L. BARNETT, OF NEW YORK, N. Y.

GOLF APPARATUS.

Application filed May 20, 1927. Serial No. 192,940.

This invention relates to an improved golf apparatus, and has for an object to provide an improved construction for indoor use, whereby the usual strokes on a full course 5 may be practiced and the ball given the usual impulse.

Another object of the invention is to provide an improved golf apparatus which is an improvement over my Patent No. 10 1,574,596.

A further object of the invention is to provide an apparatus that will so slow down and control a golf ball hit by a golf club in the regulation manner, no matter 15 with what force, that the game or practice strokes may be played indoors or on a limited space and true values as regards distance, direction, pull and slice can be estimated correctly, so that the values given on the 20 limited playing field will be approximately the same as if the ball were played on a regulation size golf course.

A further object of the invention is to provide an indoor golf course or game 25 which may be made in miniature and played with light balls and with the fingers instead of clubs.

In the accompanying drawings—

Figure 1 is a top plan view of an indoor 30 golf apparatus disclosing an embodiment of the invention, the protecting screens being shown in section.

Figure 2 is a longitudinal vertical sectional view through Figure 1 on line 2—2.

Figure 3 is a transverse sectional view 35 through Figure 1 on line 3—3.

Figure 4 is a perspective view of a modified form of the invention, showing a golf course in miniature capable of using ping- 40 pong balls or other small balls designed to be projected by the fingers.

Figure 5 is an enlarged fragmentary sectional view through Figure 4 on line 5—5.

In indoor golf courses or golf apparatus, 45 it has been difficult heretofore to simulate or approximate actual conditions of a regular course until the structure shown in my prior patent was devised. In the present invention, improvements have been added to the

50 apparatus disclosed in my prior patent in order that a better or truer value may be secured in regard to all of the strokes, and particularly in regard to the strokes known as "pulls" and "slices." In this way, a player may drive the ball as hard or as easy as he wishes with a full size club and full

size ball. After having made a stroke, the ball will strike the back wall or abutment, and by reason of the curved nature thereof, will cause the ball to bounce back and give 60 a true value to the stroke, both in regard to distance and direction.

Referring to the accompanying drawings by numerals, 1 indicates suitable sides and end, which may consist of a board five or 65 six inches high. This board may be secured to the floor of an ordinary room in any desired manner, and also secured to the main platform structure 2. Within the boards or side walls 1, is arranged a bed 11 of sand 70 as hereinafter fully described, said bed being of any desired thickness, as for instance, four or five inches thick. The device may be of any desired length, as for instance, twenty-four feet long, and the the platform 75 structure 2 is preferably provided with what may be termed standing platforms 3 and 4, which may be of ordinary carpet, rugs or other material. Arranged between the standing platforms 3 and 4, is a rug or 80 other support 5 adapted to receive a tee 6 if desired. On the tee 6 the ball 7 is placed, which is an ordinary full size golf ball. After being placed on the tee, the ball may be struck by a full size club and 85 driven with any desired force within the limits of the ability of the player. The ball is designed to strike against the abutment or wall 8, which is substantially dome-shaped at the rear so that practically all points 90 where the ball strikes will be curved in two directions, namely, horizontally and vertically, whereby the ball will glance off or bounce back at different angles according to the direction of the initial stroke. The curve 95 of the abutment 8 is such that if a ball is driven in a direct line centrally over the blocks 9, it will strike the abutment 8, bounce back onto the sand bed 11 and then roll toward the wall 12. As it strikes the bed 11, it 100 is retarded appreciably and also retarded in its rolling action, though if sufficient power is used it will strike the abutment or stop 12 and rebound again in a direction toward abutment 8.

As indicated in Figure 2, if a low substantially horizontal drive is made, the ball will strike at approximately point 10 and will rebound or bounce until it hits the sand bed 11 at approximately the point 10'. 110 After hitting this point, it will roll toward abutment 12 a certain distance. If a high

ball is driven in a straight line over the center of the blocks 9, similar to the drive just mentioned, it may strike the point 31 and bounce back to approximately the point 31'.
 5 From point 31' it will roll toward the abutment 12 and stop at the same place where the former ball stopped, provided both balls were driven with the same power. It will be noted that the balls in the two drives
 10 will strike the bed 11 at different angles, whereby the relative distance from the tee will be compensated. After the ball strikes the sand bed at point 10', it will roll farther on the sand bed than a ball given the same
 15 momentum will roll when striking the sand bed at point 31', but by reason of the fact that point 31' is in advance of point 10', both balls will stop at the same point. In this way, the same drive, whether high or
 20 low, will make the same credit. It will be evident that different rules may be used with the game, but usually the rules are such that the greatest value will be given if the ball lands in some of the center blocks or sections 9. For instance, if the ball strikes the wall or abutment 8, rebounds to a point on bed 11, rolls along this bed, strikes the abutment 12 and rebounds a second time toward the approach block 13 until it reaches
 25 the block 9', the value of the stroke will be two hundred yards. If the ball should move over to the block or section 14, ten yards is subtracted so that a credit of one hundred and ninety yards will have been secured.
 30 The blocks 9', 14 and also the remaining blocks, are formed by the respective strings 15 and 16 resting on the sand bed 11 and secured in any way to the sides 1. At a convenient point along the sides, the various numbers 17 are arranged for indicating the value of the stroke where the ball rebounds from the abutment 12. On the opposite side of the course are arranged the numbers 18 which give the value of the balls striking
 35 the wall 8 and rebounding toward abutment 12 but not reaching said abutment. As each of the blocks formed by the cords or strings 15 and 16 equal a distance of three yards, a person can readily ascertain the value of the
 40 drive.

In playing the game, if the first stroke only makes a credit, of say one hundred and forty, and the first hole is two hundred yards from the tee, a second stroke will be necessary to make up the difference, namely, the sixty yards. Different rules may be provided to vary the values without departing from the spirit of the invention, but the apparatus will function in the same manner, regardless of the particular rules used. When a ball strikes the wall or abutment 8, it will always rebound at an angle in proportion to the angle at which it strikes the wall 8, so that when the ball is off the center line, a substantially true value of the

slice or pull will be given, whereby the player will know exactly how much deviation from a perfect stroke has been made. When making a second or third stroke necessary to make up the sixty yards mentioned, the block 13 is used as an approach block and the various blocks 9, 14 and the like, may be given different values, as for instance, the value of one yard or some other distance, whereby each stroke after the first 70 stroke will add distance to the first stroke and thereby permit the player to approach the first hole.

Usually in practicing with the apparatus, the balls will pass within the confines of the 80 abutment 8, but if for any reason they should not, the screens 19 and 20 hung from the ceiling or any suitable support, will prevent the balls from leaving the bed 11. Under some circumstances, it is desirable to 85 use the apparatus as a parlor game for the purpose of amusement, rather than exercise or practicing strokes. When this is the case, the structure shown in Figures 4 and 5 is used. In this form of the invention, 90 the structure is almost identical with the other form, but preferably the structure is made much smaller, as for instance, with a bottom or base 1' of wood three or four feet long and of any desired width. As shown 95 in Figure 4, the bed 21 is identical with the bed 11 and the wall 22 is identical with wall 8 except for size. However, instead of having a platform 2 with the members 3 and 4 and the supporting tee as shown in 100 Figure 1, a pair of wires 23 is provided and preferably connected to the uprights 24 and 25. This will support the ball 26 which is a very light ball, as for instance, an ordinary ping pong ball. When the ball is in 105 the position shown in Figure 4, it is flipped with one of the fingers and caused to strike the wall 22 from which it bounces back and onto the bed 21. The ball acts in a similar manner to the golf ball used in the structure shown in Figure 1, and the rules of 110 the game and values of the strokes are preferably the same.

After one or more strokes have been made and the ball has reached a point within 115 twenty yards of the approach block 27, it is removed and placed on the line 28 opposite any of the numbers 29, according to the distance it was from the approach block 27. For instance, if it was eighteen yards from block 27, it would be placed on line 28 opposite the numeral 18 on the line of numbers 29. The ball is then flipped with one of the fingers in order to force the same into the hole 27'. Instead of placing the ball on 120 line 28, it could be placed at some other point on the putting green 30 but must be placed at an equal distance from the hole 27'. The putting green 30 is preferably a bed of sand, 125 similar to bed 21 and supported by the 130

platform 31 which may be wood or other desired material.

In this form of the invention, the apparatus has been reduced to a game and the ball is moved by the fingers, but preferably by a flipping action. In the preferred form of the invention shown in Figures 1 to 3 inclusive, the apparatus is much larger and a full size ball and full size clubs are used so that the ball may be hit with as much power as desired with any of the usual clubs now in common use.

What I claim is:

1. In an indoor golf apparatus, a tee, a field divided into areas having predetermined values, a wall at the rear of said field against which a golf ball is adapted to be projected and from which the golf ball rebounds into one of the areas of said field to determine the value of the stroke by which the golf ball was projected, said wall being curved in two directions.

2. In an indoor golf apparatus, a tee from which a golf ball is adapted to be projected, a field into which the golf ball is adapted to be projected, said field being divided into a plurality of individual areas, each area having a predetermined value whereby the value of the stroke projecting the ball will be determined, and an abutment arranged adjacent one end of said field, said abutment being substantially dome-shaped whereby a ball striking the abutment will bounce back at the opposite angle at which it strikes the abutment whereby the deviation of the ball from a perfect shot may be ascertained.

3. In an indoor golf apparatus, a tee, a field divided into areas having predetermined values, a substantially dome-shaped wall at the rear of said field against which a golf ball is adapted to be projected from said tee, said ball being adapted to rebound from said wall into one of the areas of the

field, and a second wall arranged adjacent 45 said tee, said ball being adapted to rebound from said second wall after having first rebound from the first wall.

4. In an indoor golf apparatus, a tee, a field divided into areas having predetermined values, a substantially dome-shaped wall at the rear of said field against which a golf ball is adapted to be projected and from which the golf ball rebounds, and a flat straight wall arranged near said tee for 55 receiving said ball after it rebounds and causing the same to rebound a second time into one of the areas of said field whereby the value of the stroke is ascertained.

5. In an indoor golf apparatus, a tee, a field divided into areas having predetermined values, a wall substantially arc-shaped in cross section at the rear of said field against which a golf ball is adapted to be projected and from which the golf ball 65 rebounds, and a straight flat wall arranged adjacent said tee for receiving said ball after it rebounds and for causing said ball to rebound a second time into one of the areas of said field to determine the value of the 70 stroke by which the ball was projected.

6. In a golf game apparatus, a field in which a golf ball is adapted to be projected, a wall at the rear end of said field against which the golf ball is adapted to be projected and from which the ball rebounds, a pair of resilient wires acting as a tee for said ball, and a second rebound wall arranged adjacent said tee.

7. In a golf game apparatus, a field divided into areas having predetermined values, a tee formed of a plurality of wires arranged adjacent one end of said field, a wall arranged adjacent the opposite end of said field, a rebound wall arranged adjacent said tee, and means forming a putting green mounted upon said field.

EDWARD L. BARNETT.
